MIXING JET APPARATUS

Harold O. Malcolm, Augusta, Kans., assignor to
Socony-Vacuum Oil Company, Incorporated,
New York, N. Y., a corporation of New York

Application July 24, 1941, Serial No. 403,836

2 Claims. (Cl. 196—46)

This invention has to do with mixing jets, particularly with mixing jets wherein a reagent is mixed with an oil to be treated.

In several methods of treating oils, particularly that method set forth in U. S. Reissue Patent 20,938 to Charles O. Hoover, and known commercially as the "slurry" method of copper sweetening, a slurry of solid absorptive material, such as fuller's earth, for example, is admixed by induction with an oil to be treated. In the method in question, the treating apparatus, as shown by Hoover, consists of a reaction tube discharging into a conical bottomed settling chamber, in the bottom of which the solid adsorptive material impregnated with reagent is settled, and an eductor or injector, in which the motive fluid is the oil to be sweetened, which injector is attached by a pipe to the bottom of the settling chamber so that the settled slurry of solid adsorptive material may be withdrawn therefrom by the eductive action of the injector and which injector discharges into the reaction tube above mentioned.

Due to the necessity for securing complete re-action in a very short time, the injector-mixer must secure a very high turbulence to accomplish a complete mixing and complete reaction in the fraction of time, (a matter of fractional seconds), permissible for the reaction. Due to this high turbulence, combined with the somewhat abrasive nature of the solid adsorptive material very serious corrosion and erosion occurs within the injector-mixer. At the same time, the process entails the necessity of close control over the proportioning of injection fluid, (oil to be treated), and educted material, (solid adsorptive material plus reagent), and consequently must be so constructed that this accuracy may be maintained over a comparatively long period of commercial operation in the face of the above noted erosion and corrosion.

This invention has for its object the provision of an eductor-mixer of the type noted capable of achieving a high degree of turbulence and at the same time capable of achieving continuous close control of the mixing of a light fluid and a slurry of solid adsorptive material, and also capable of convenient and easy replacement of parts when worn.

The invention may be readily understood by reference to the drawing attached hereto, the single figure of which shows, in section a mixing valve constructed in accordance with this invention.

Referring now to the drawing, there is shown a

valve body 1, comprising a discharge tube 2, an injection fluid inlet tube 3, an eduction tube 4, and a mounting tube 5 upon which the gland, hand wheel, and yoke of a needle valve, not shown, may be mounted for control of the lateral position of needle 6, the valve mounting tube 5 being isolated from the injection tube 3 by partition 7 and sleeve 8 positioned therein. The discharge tube 2, eduction tube 4 and injection tube 3 are supplied with the usual flanges 9, 10, 11. Within the body of the valve 1 between the induction tube 3 and the mixing chamber 12, and axially aligned with the needle 6 there is provided a jet block 13 having an inner conical passage 16, and the end of this block 13 is threaded to receive a throat nut 14, which has an inner passage formed as a continuation of passage 16 and which is so bevelled at 15 as to provide a relatively sharp edged orifice at the 20 end of that passage. The throat nut 14 and needle 6 cooperatively provide a needle valve and seat by which the flow of injection fluid may be controlled. The external portion of the throat nut 14 is hexagonally or otherwise so 25 shaped as to permit the engagement of a socket wrench therewith for removal.

In the discharge tube 2, the usual Venturi throat would be inappropriate because of its tendency to quench turbulence and would also be 30 subject to great erosion. In the present device, there is provided a cylindrical discharge throat 17, provided at its front end, (mixing chamber end), with a sharp edge 18, at its out-board end with a flange 19 by which it may be 35 secured in place when flange 9 is joined with its companion, and supported in a centrally aligned position by ring 20, which also serves to prevent substantial circulation of mixed fluids into the dead space 21.

40 The advantages of this device are in part as follows:

The cylindrical shape of the mixing chamber 12 cooperating with the sharp edge 18 of discharge throat 17 serve to create a violently turbulent mixing action across a wide range of flow 45 of injection fluid, which turbulence is maintained by the cylindrical form of the discharge throat 17. This high turbulence of fluid containing a solid adsorptive material creates highly erosive conditions, the cutting action being concentrated in the areas defined by the mixing chamber side of throat nut 14 and the interior of discharge throat 17. Due to the form of construction here adopted, both of these parts not 50 only may be made of materials highly resistant

to such action, as highly hardened steels, but they may also be very quickly and easily replaced.

I claim:

1. An eductor-mixing device comprising an injection tube, a hollow cylindrical body of substantially uniform internal cross-section throughout its length connected thereto, said body having a radial eduction port therein, a needle valve, a seat for said needle valve disposed concentrically in said body with its discharge end substantially centrally underlying said eduction port, a cylindrical discharge tube of substantially lesser external diameter than the internal diameter of said body, and an annular flange 15

supporting said tube concentrically in said body with its ingress end in a plane substantially tangent to said port, said flange lying in a plane parallel and close to the plane of the ingress end of said tube, whereby the flange serves to define a portion of the mixing chamber wall against which material will impinge during operation.

2. A device according to claim 1 in which said seat is replaceable and is internally formed to provide a passage of rapid taper, of not less than about 40° included angle, and terminates in a plane normal to the plane of said port, intersecting the latter substantially diametrically.

HAROLD O. MALCOLM.
